UNITED STATES PATENT OFFICE.

DOUGLAS VICTOR ESKELL, OF NEW YORK, N. Y.

MEANS FOR SUPPORTING AND TENSIONING TENNIS NETS AND THE LIKE.

Application filed October 29, 1921. Serial No. 511,251.

To all whom it may concern:

Be it known that I, DOUGLAS VICTOR ESKELL, a subject of the King of Great Britain, and resident of New York city, in the county of New York and State of New York, have invented certain new and useful Improvements in Means for Supporting and Tensioning Tennis Nets and the like, of which the following is a specification.

10 The invention relates to an adjustable connection between the cable at the upper edge of a tennis net and the post or other support at one or both ends of the net.

15 It is a usual practice in the mounting of tennis nets to wrap the cable at the upper edge of the net about a cleat carried by an end post, but in these cases a severe strain is placed on the portion of the cable engaging the cleat resulting in a wear of the fibre at this point and an eventual sagging 20 of the net as a whole. Attempts have been made to remedy this condition by passing the end of the cable about winding drums and other forms of take-up devices but this 25 involves the use of expensive mechanical constructions which are not easily handled and must be either left exposed to the elements when not in use, or which involves the transportation of the heavy mechanism 30 when the net is taken down.

Accordingly, the primary object of the invention is to provide a simple form of construction by means of which the net can 35 be mounted in position and securely connected to the post or other support without deleterious wear on the connecting parts, and which at the same time will provide a 40 convenient means for adjusting the tension on the net without providing complicated mechanism to effect this result.

Incidental to this general desideratum it 45 is among the other objects of the invention to provide a structure which can be demounted with the net and which can be easily carried with the net and without the addition of any material excessive weight to be ported.

Still another object of the invention is to 50 provide a form of connection between the net and post, which when set in operative position will not possess any "give" or loose play and in this way will tend to minimize any tendency of the net to sag at its center.

55 The invention further features a demountable post structure and associated connec-

tion with the net which can be marketed as a complete article of manufacture and readily secured to any net.

Various other objects and advantages of 60 the invention will be in part obvious from an inspection of the accompanying drawings and in part will be more fully set forth in the following particular description of one form of mechanism embodying my invention, and the invention also consists in certain new and novel features of construction and combination of parts hereinafter 65 set forth and claimed.

Referring to the accompanying drawing: 70 Figure 1 is a view in elevation showing one end of a tennis net secured to a post by a connection constituting a preferred embodiment of the invention and also showing an improved form of post for the purpose herein outlined;

75 Figure 2 is a detailed view of the upper end of the post shown in Figure 1 looking at the same from the side of the showing in the first figure; and

80 Figure 3 is a transverse sectional view taken on the line 3—3 of Figure 1, looking in the direction indicated by the arrows.

85 In the following description and in the claims, parts will be identified by specific names for convenience of expression but they are intended to be as generic in their application to similar parts as the art will permit.

90 In the drawings there is shown a post 10 for supporting one end of a tennis net 11 which net is provided at its upper edge with a cable 12 all as is usual in well known constructions of this character. The post is provided with a cap 13 which is fitted over 95 the same and extends downwardly some material distance along the length of the post to minimize any tendency of strains on the cable reacting on the cap to remove the same from the post. The cap is provided at its upper side with an upstanding fork-like member 14 which includes two prongs 15 coacting to form a link receiving circular socket 16 therebetween. The end of the cable 12 is looped through the end link 17 of 100 a short length of chain 18 which constitutes, in effect, a continuation of the cable. As tennis nets are usually mounted between a pair of end posts it will be understood that the chain connection shown in Figure 1 is 105 duplicated at the opposite end of the net. The prongs 15 are so designed that when the

chain is in the operative position shown in Figure 1, one of the links, such as the link 19, is disposed in upstanding position and fitted in the socket 16 and between the contiguous ends 20 and 21 of the adjacent links. In this way it will be appreciated that any one of the links may be positioned in the socket and the ends of the next adjacent links constitute stops which are spaced apart so as to engage the prongs 15 and in this way limit any bodily movement of the chain past the post. The surplus end of the chain simply falls loose as indicated in Figure 1, but as tennis nets require relatively small adjustment to give them their variously desired tension, a relatively short length of chain may be used and in this way economy in weight is effected. The character of chain used will depend largely upon the required range of adjustability in tension on the net and usually small links will be employed for obviously the smaller the length of each link the greater is the possibility of making small adjustments in the tension on the net.

It is herein suggested that the cap may be either a separate member from the post or may constitute a structural part of the post and it is further suggested that the post may be removable with the attachment as a complete unit. For this purpose there is disclosed in Figure 1 a ground anchor 22 provided with a post receiving socket 23 into which the lower end of the post 10 may be inserted.

In such constructions it has been found to be of commercial advantage to make the post of metal and in the suggested showing the post is formed of a metal tube 24, the upper end of which is closed by the cap 13. It is obvious within the scope of the disclosure that the post may be mounted for rotary movement about its vertical axis so as to bring the socket 16 in line with the net, or the cap may be rotatably mounted on the post and is preferably in screw threaded engagement with the post. In this way the cap can be rotated on the fixed post so as to align the socket with the net.

In operation the person mounting the nets simply drops one link of the chain into the socket of one post, goes to the other post and placing the necessary tension on the other chain and cable draws the chain over the cap. When the desired tension is attained the link disposed over the post is

drawn down into the socket on the post and in this way secures engagement with the post. It is of course possible to center the net by readjusting the link which engages either of the sockets but after a net has been once mounted the operator would usually know which of the links should be in engagement with their respective posts. Should the net sag during the progress of the game it is simply necessary to lift up the chain at one end of the net and position the next link nearer the net into the post socket.

While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I claim:

1. In a device for securing a tennis net cable under tension, the combination with an upright post and a tennis net provided with a cable, of adjustable means for securing the cable to the post, said means including a cap fitted to the upper end of the post and provided with a U-shaped link socket projecting upwardly therefrom and a link chain secured to the cable and adapted when the cable is stretched towards the post to have any of the links of the chain engaging in the socket thereby to hold the net in its stretched position.

2. In a device for securing a tennis net cable under tension, the combination with an upright post, and a tennis net provided with a cable, of means for securing the cable to the post, said means including a cap provided with a post receiving socket and with a chain receiving socket and a chain formed of a plurality of links secured at one end to the cable and adapted when the chain and cable are stretched towards the cap to have one of the links engage the chain receiving socket whereby the cable may be held securely while under tension.

Signed at New York city, in the county of New York and State of New York, this 24th day of Oct. A. D. 1921.

DOUGLAS VICTOR ESKELL.
